FRANK A. AUSTIN, OF SYRACUSE, NEW YORK

FUEL GRATE

Application filed November 14, 1929. Serial No. 407,118.

This invention relates to a heater-grate for receiving and supporting coal, coke and other solid fuels for combustion adapted to replace impaired or less efficient grates in old or new heaters.

In the use of hot water or steam for heating purposes the heaters are usually provided with water chambers surrounding the combustion chamber and extending from approximately the level of the fuel grate upwardly to the top of or above said chamber, the cold water to be heated being introduced into the lower part of the water chamber to be heated by the combustion of the fuel and circulated through the heating system either as hot water or steam.

Likewise in the use of warm air for heating purposes the combustion chamber is surrounded more or less by an air chamber extending from approximately the level of the grate some distance above the combustion chamber, the cold air being usually introduced into the lower portion of the air chamber to be heated by the combustion of the fuel in the combustion chamber.

It therefore follows that the efficiency of the heater, whether hot water, steam or warm air, depends largely upon the ability to, and rapidity of transfer of the heat from the products of combustion to the cold water or cold air in the water or air chambers in transit from the bottom of said chambers to the exit openings thereof leading to the distributing pipes.

It is also well known that the efficiency of transfer of the heat from the combustible products to the water or air is dependent largely upon a proper distribution of the air draft through the grate and also upon the distribution of the ash residue upon the grate.

The main object of the present invention is to provide a fuel grate constructed and arranged and adapted to be adjusted in such manner as to effect a more complete combustion of the fuel, a more rapid transfer of the heat from the combustion chamber to the heating agent, a more efficient separation of the ash from the fuel and a more efficient distribution of the air from the underside up-

wardly through the grate and fuel than has heretofore been practiced.

Another object is to construct the grate in sections of such size that they may be easily and quickly installed in place within the heater through the fuel inlet or ash outlet without disturbing any of the other parts of the heater other than merely opening the fuel door or the ash door.

A further object is to enable these sections to be placed in operative position without the use of special tools.

A further object is to provide simple and efficient means whereby the grate may be shaken through different arcs of movement or to a dumping position without changing the plane of movement thereof.

Other objects and uses relating to specific parts of the grate will be brought out in the following description.

In the drawings:

Figure 1 is a top plan of a heater grate embodying the various features of my invention, the grate sections being shown in their normal positions for receiving the fuel.

Figure 2 is a vertical sectional view taken in the plane of line 2—2, Figure 1.

Figure 3 is a horizontal detail sectional view partly broken away, taken in the plane of line 3—3, Figure 2.

Figure 4 is a horizontal detail sectional view taken in the plane of line 4—4, Figure 2.

Figures 5 and 6 are horizontal sectional views taken respectively in the planes of lines 5—5 and 6—6, Figure 2.

Figure 7 is a vertical detail sectional view taken in the plane of line 7—7, Figure 5.

Figure 8 is a detail vertical sectional view taken in the plane of line 8—8, Figure 7.

Figure 9 is a detail vertical sectional view taken in the plane of line 9—9, Figure 1.

Figures 10 and 11 are enlarged detail sectional views taken respectively in the planes of lines 10—10 and 11—11, Figure 9.

Figure 12 is an enlarged horizontal sectional view taken in the plane of line 12—12, Figure 9.

In many of the different types of heaters now in common use the frame work of the ash box is usually provided with front and

rear sockets or openings for receiving the ends of the grate bars or suitable supporting rods for other forms of grates and applicant has sought to utilize these sockets or openings 5 as far as is practicable in the different types of heaters for the reception of his grate-supporting means which, in this instance, consists of a pair of similar rods or bars —1—, either tubular or solid, arranged in the same 10 horizontal plane in parallel transversely spaced relation to extend forwardly and rearwardly of the ash box with their front and rear ends resting respectively in the pre-formed sockets or openings —a— in the front 15 and rear upper portions of the ash box —A—, partly shown in Figure 6.

These grate supporting bars preferably consist of cylindrical tubes of uniform diameters having their front ends provided with 20 adjustable collars —1'— adapted to engage the inner face of the front wall of the ash box —A— to hold the rods against forward displacement while the rear sockets —a— are usually closed at the rear ends and serve to 25 hold the rods —1— against rearward displacement.

A skeleton grate-supporting frame or spider —2—, which is of more or less rectangular form in top plan, is supported in 30 a manner presently described upon the upper faces of the rods —1— substantially co-axial with the axis of the combustion chamber (not shown) and comprises a central tubular hub —3— having a plurality of, in this instance 35 four, radial spokes or arms —5— arranged in uniformly spaced relation circumferentially and connected intermediate their ends by angular tie bars or webs —6— which constitute an outrigger for supporting and holding 40 the arms —5— against vertical and circumferential movement relatively to each other.

The opposite sides of each of the webs or tie bars —6— converge outwardly at approximately 45 right angles to the radial arms 45 —5— so that their apexes will be disposed approximately midway between the radial arms.

The apexes as —7— are preferably truncated and when the skeleton frame is placed in operative position its radial arms —5— will be disposed at angles of approximately 45 degrees to the supporting rods —1— thus bringing two of the opposite apexes in a 55 plane substantially midway between the rods —1— while the other two apexes will be disposed at the outside of said rods.

The radial arms —5— and webs —6— connecting them extend diagonally across the 60 upper faces of the supporting rods —1— as shown more clearly in Figure 6, said arms —5— being provided at their outer ends with inwardly extending T-shaped slots —8— as shown in Figures 6, 7 and 8 for receiving the T-shaped upper edges of a corresponding

number of extension slides —9— which project downwardly through the open lower sides of the slots —8— some distance below the lower edges of the arms —5— and are provided in their lower edges with concave 70 seats —10— adapted to engage the upper faces of the rods —1— for centering and holding the skeleton frame —2— in its adjusted position.

These slides —9— are elongated radially 75 and may be made of any suitable height or vertical depth for supporting the frame —2— and grate sections carried thereby at the desired level according to the construction of the heater in which the grate is placed.

The object of these sliding extensions —9— is to enable the same grate-supporting frame —2— to be used in heaters of different sizes where the spacing of the supporting rods —1— may vary and also to permit the replacement of said slides by others of different vertical heights according to the various levels of the combustion chambers of different heaters, said slides being held in their 80 adjusted positions by set screws —11— which are engaged in threaded apertures therein and with overlying portions of the arms —5— as shown in Figures 7 and 8.

The upper surfaces of the apexes —7— of the frame —2— are substantially flat and are disposed in a plane some distance above that of the upper surfaces of the radial arms —5— to form out-bearings for the next adjacent superposed grate sections presently described.

The upper end of the hub —3— of the frame —2— extends some distance above the horizontal plane of the upper faces of the apexes —7— and is provided with a plurality of, in this instance four, similar circumferentially elongated peripheral recesses —12— registering with the arms —5— of the frame —2— for receiving pendent flanges on the inner ends of the next adjacent superposed grate section and thereby locking said section to the supporting frame against relative rotary movement thereon, the arms —5— being provided with lugs —13— projecting upwardly from their upper faces adjacent the periphery of said flanges to hold the sections against radial displacement as shown more clearly in Figures 6 and 7.

The hub —3— of the spider frame —2— is provided with a central cylindrical bore for receiving the pendent hub of one of the 120 superposed grate sections in a manner presently described as shown more clearly in Figures 2 and 7.

A plurality of, in this instance four, similar and interchangeable grate quadrant-segments —14— are assembled edge to edge circumferentially upon the supporting frame —2— around the upper portion of the hub —3— and are provided at their inner ends with pendent flanges —15— complementary 125

to the recesses —12— in which they are operatively seated with their lower edges abutting against the inner faces of the corresponding lugs —13— thereby locking said segments against relative circumferential or radial displacement as shown more clearly in Figures 6 and 7.

These segments are provided with pendent lugs —16 (Figures 6, 7 and 8) having their lower edges provided with recesses —16'— complementary to the adjacent portions of the arms —5— upon which they are saddled to form out-bearings supporting the major portions of the segments —14— and additionally holding them against circumferential movement relatively to each other and to the supporting frame —2—.

These segments are arranged substantially radial to the axis of the hub —3— with their medial lines in vertical alinement with and directly over the corresponding arms —5— of the supporting frame —2— so that each segment will be supported at four points, one near the hub —3—, a second near the outer end of the corresponding arm —5— just beyond the adjacent portions of the tie webs —6—, the third and fourth being upon the upper surfaces of the apexes —7— at opposite sides of the corresponding segment from its normal horizontal plane.

The opposite edges of each segment converge inwardly from the periphery toward the center of the grate and are provided with recesses —17— each of which is adapted to register with that of the next adjacent segment to form relatively large openings through which the ashes may be dumped when the superposed grate segments are adjusted to certain positions in a manner presently described.

These grate segments —14— extend radially some distance beyond the marginal webs —6— and are provided with radial slots —18— extending inwardly from the periphery thereof to permit ashes to pass therethrough, the intermediate portions of said segments being provided with additional parallel slots —19— arranged in circumferentially spaced relation with the central slot substantially radial to the axis of the hub —3— to further provide for the discharge of ashes therethrough.

As illustrated more clearly in Figure 5, the peripheries of the segments —14— are concentric with the axis of the hub —3— while the opposite edges of each segment will be approximately tangential to the arcs of curvature of their inner edges and therefore divergent outwardly, the outer portions of the segments beyond the openings —17— being disposed in substantially radial planes and in juxtaposed relation to form intervening slots corresponding approximately to the slots —18—.

65 The upper surfaces of these segments

—14— are disposed in substantially the same horizontal plane except that they are provided intermediate their outer and inner edges with raised bosses —20— arranged equal distances from the axis of the hub —3— 70 and having their upper surfaces convexed circumferentially to form out-bearings for the adjacent portions of the superposed rotatable grate sections presently described.

Each segment is provided with a plurality 75 of, in this instance four, of the bosses —20— arranged respectively near the meeting edges of the segments and equal distances from and at opposite sides of the radial centers thereof as shown more clearly in Figures 2 and 5. 80

If desired, the opposite edges of each segment along the adjacent recesses —17— may be serrated at —21— so that a portion of the ashes may fall through the grooves thereof as shown in Figure 5. 85

A hub —22— is extended from the top downwardly through the cylindrical bore of the hub —3— and is provided with a central air draft opening —23— from top to bottom thereof, the upper end of said hub being provided with an annular enlargement —24— overhanging the upper end of the hub —3— and journaled thereon through the medium of anti-friction balls —25— to permit the hub —22— to be rotated with a minimum amount of friction, said annular enlargement —24— being provided with a pendent annular flange —26— surrounding the bearings —24— to protect the same against accumulations of ashes and other foreign matter. 95

The perimeter of the extreme upper end of the hub —22— is preferably square or angular in cross section, as shown more clearly in Figure 3, for receiving the hub as —27— of rotatable grate section —28— having diametrically opposite grate segments —29— integrally united to corresponding sides of the hub —27— and extending radially therefrom. 100

The hub —27— is provided with a central square or angular openings —30— complementary to the square upper end of the hub —22— for receiving the same and thereby locking the hub and grate section to each other against relative rotary movement and at the same time assuring simultaneous rotation of both of those parts when the hub is rotated or adjusted angularly about its axis in a manner hereinafter described. 110

The grate section —28— is of substantially the same diameter as the underlying segmental grate composed of the segments —14— but the segments —29— are of less peripheral length than the segments —14— or in other words somewhat less than quadrants, the opposite edges of each segment —29— being arranged to diverge outwardly at equal angles to their longitudinal centers and approximately tangential to a circle inscribed within the square opening —30— in the hub —27— so that when in their normal positions they 120 125 130

will overlie and extend some distance beyond the corresponding discharge opening —17.

An additional hub —31— is placed over and upon the hub —27— to extend across the upper end of the hub —22— in spaced relation thereto, said hub —31— being provided with diametrically opposite radially projecting wings or segments —32— of substantially the same form as the segments —29— of the hub —27—, the hub —31— and its segments —32— constituting another grate section having its wings or segments —32— extending radially at right angles to the center lines of the segments —29—.

In other words both of these grate sections are rotatable and are arranged at right angles to each other and suitable means is provided for transmitting rotary motion from the grate section —28— to the grate section as —33—.

For this latter purpose the hub —27— of the grate section —28— is provided with diametrically opposite peripheral recesses —34— midway between the segments —29— and are preferably elongated circumferentially to receive complementary portions —35— on the inner ends of the segments —32— of the grate sections —33— so that when the latter is placed over and upon the hub of the section —28— the portions —35— will automatically enter the recesses —34— and thereby lock the two sections together to rotate in unison when the hub —22— is rotated.

It will be noted upon reference to Figures 1, 2 and 3 that the segments —29— and —32— of the sections —28— and —33— respectively are disposed in substantially the same horizontal plane while the hub of the section —33— is elevated above that plane and capped over the upper end of the hub —22—, the portion of the hub —31— overlying the upper end of the hub —22— being provided with perforations —36— to permit the passage of air from the interior of the ash box upwardly through the tubular hub —22— and thence into the combustion chamber.

An ash receiving and retaining ring —37— is placed telescopically over and upon the central hub —31— of the section —33— and is provided with a downwardly projecting marginal flange —38— resting upon the upper faces of the segments —29— and —32— around the hub —31— as shown more clearly in Figure 2, said ring being also provided with an upwardly projecting marginal bead —39— for retaining a limited quantity of the ash which may accumulate within the bead.

The lower side of the ring —37— within the marginal flange —38— is provided with air channels —40— communicating with the central opening in the ring, the inner walls of which are arranged in spaced relation to the central portion of the hub —31— to allow the air to pass from the underside upwardly through the ring into the combustion chamber.

The wings —29— of the grate sections —28— are provided with radial slots —41— extending inwardly from the periphery thereof of similar to the slots —18— of the grate segments —14—, the intermediate portions of said wings —29— being provided with additional slots —42— arranged in parallel spaced relation with the central slot substantially radial to the axis of the grate.

In like manner the wings —32— of the grate sections —33— are provided with slots —43— extending inwardly from the periphery thereof, the intermediate portions of said wings being provided with additional slots —44— arranged in parallel spaced relation in which the central slot is substantially radial to the axis of the grate as shown more clearly in Figure 1, the slots —18—, —41— and —43— of the segments —14—, —29— and —33— respectively being arranged in substantially uniformly spaced relation circumferentially while the slots in the intermediate portions of said segments are also arranged in uniformly spaced relation circumferentially but at an angle to the peripheral slots of their respective segments.

It will be observed upon reference to Figures 1 and 2 that the wings —29— and —32— of the grate sections —28— and —33— rest upon the raised bosses —20— of the segments —14— and are thereby held in spaced relation to the underlying segments to allow clearance for the ashes and also to facilitate the breaking up of any clinkers which may lodge upon the grate sections —14— between the segments —29— and —32— as the latter are rotated or shifted circumferentially for shaking purposes.

It will also be noted upon reference to Figures 1, 2 and 3 that when the grate sections —28— and —33— are placed in operative position the flanges —35— on the inner ends of the segments —32— will project into the corresponding recesses —34— in diametrically opposite sides of the grate sections —28—, thereby locking the two sections —28— and —33— to each other against relative rotation with their respective segments —29— and —32— disposed in substantially the same horizontal plane and in uniformly spaced relation circumferentially.

As previously stated, the segments —29— and —32— are of uniform circumferential width somewhat greater than that of the openings —17— between the grate segments —14— and normally overlying said openings as shown in Figure 1, while the spaces between the said segments are slightly greater than the openings —17— to enable the ashes and clinkers to be dumped when the sections —28— and —33— are shifted circumferentially to register the spaces between the segments —29— and —32— with the openings —17—.

The outside diameter of the ash supporting

ring —37— is slightly less than the radius of the grate sections 28 and 33 and, when the ring is in operative position it will overlie adjacent interlocking portions of said sections thereby carrying a considerable portion of the main body of the ash and fuel and permitting the movable sections to be shifted circumferentially relatively to the ring in case the friction between the ring and fuel supported thereby should exceed that between the ring and sections, while the space —27— between the ring and hub of the grate section —33— together with the apertures —36— in the top of said hub, permit free circulation of air from the underside upwardly to the fuel to reduce the liability of burning out of the hub or ring.

Shaking and dumping

20 The upper end of the hub —22— is supported upon the ball-bearings —25— while its lower end extends some distance below the lower end of the hub —3— of the supporting frame —2— into the upper portion 25 of the ash box (not shown) and is provided with a square or angular perimeter for receiving a collar —45— having a corresponding angular opening adapted to fit more or less closely upon said perimeter.

30 This collar is provided with a radially extending crank arm —46— forming a part of a shaking mechanism and is adjustable vertically along and upon the hub —22— as may be required upon different types of heaters, 35 said collar being held in its adjusted position by a set screw —47— and also held against downward displacement by a cotter key or pin —48—, shown in Figures 2, 3 and 4.

The outer end of the crank arm —46— is 40 provided with a series of, in this instance three, upwardly projecting pivotal pins —49— arranged at different distances from the axis of the hub —22— for receiving the rear end of a forwardly projecting link 45 —50— having its front end pivotally connected by a pin or bolt —51— to the intermediate portion of a shaking lever —52—, shown more clearly in Figures 1, 6 and 9.

The link —50— is extensible and for this 50 purpose is composed of lengthwise sections —53— and —54— pivotally connected respectively to the crank arm —46— and to the hand lever —52— and having their adjacent ends overlapping one upon the other and provided respectively with a plurality of apertures —55— and —56— for receiving a clamping bolt —57—, the apertures —55— being arranged in equally spaced relation lengthwise of the section —53— while the 60 apertures —56— in the section —54— are arranged one and a half times the distance apart than the apertures —55— so as to obtain a relatively close adjustment of the sections, one upon the other.

65 The overlapping portions of the sections

—53— and —54— are provided with flanges —58— and —59— respectively adapted to engage corresponding edges of the sections —53— and —54— to guide them in their adjustment, one upon the other, and also to hold them against relative rocking movement about the axis of the clamping bolt —57—.

If desired, the pivotal pins —49— on the crank arm —46— may be provided with apertures for receiving a cotter key or pin —60— 75 to hold the adjacent end of the link —50— against upward displacement.

It will be noted that the link —50— is free to swing horizontally about the axis of the pivot —49— to which it is connected, the object of such swinging movement being to permit the link to be brought through different parts of the ash box as may be required for different types of heaters.

The hand lever —52— comprises lower and upper lengthwise sections —61— and —62—, the lower end of the section —62— being provided with an angular socket —63— for receiving a corresponding angular upper end —64— of the lower section —61—. The adjacent ends of the sections —61— and —62— are provided with transverse apertures for receiving a clamping bolt —65— by which the sections are secured and held against endwise displacement while the seating of the head —64— in the socket —63— serves to hold the sections against lateral displacement.

The intermediate portion of the section —61— is provided with a lengthwise slot —66— for receiving the pivotal pin —51— and permitting the rocking movement of the hand lever while the link —50— remains in a substantially horizontally plane is sliding engagement with the upper edge of the bracket —72—.

The lower end of the lever section —61— is provided with a ball terminal —67— adapted to enter any one of a series of, in this instance three, sockets —68— which are formed in the upper side of a supporting member —69— as shown more clearly in Figure 9, the lower ends of said sockets being provided with branch openings —68'— to allow the escape of ashes or other foreign matter which may tend to lodge in the sockets.

The front end of the ring section —54— is arranged in a vertically elongated slot —66'— in the lever section —61— and is mounted upon a reduced portion of the pivotal bolt —51—, said reduced portion being also adapted to receive a spacing sleeve —51'— which is arranged in one of the slots —66— and is of greater length than the adjacent side wall of the slot —66'— to turn with the pivotal bolt when the latter is tightened thereby preventing binding of the lever section —54— against the opposite walls of the slot —66'—.

The lever support —69— is adapted to be 130

adjusted laterally in a horizontal plane to conform to different positions or angles of adjustment of the link —50— and hand lever —52— carried thereby and for this purpose its rear end is pivoted by bolt —70— to an underlying flange —71— of a bracket —72—, which in turn is secured by bolts —73— to the outer face of the adjacent portion of the ash box —A— as shown in Figure 9.

10 This bracket —72— is provided with a forwardly projecting flange —74— adapted to enter any one of a series of, in this instance five, radial slots —75— in the rounded rear end of the lever support —69—, to assist said bolt in firmly holding the member —69— in its adjusted position.

Assembly

20 The main supporting rods or bars —1— are first placed in operative position in their respective sockets in the front and rear portions of the ash box, usually at opposite sides of the ash door opening through which the members —1— are passed, after which the 25 spider frame —2— is placed through the same door opening and upon the supporting bars —1— in the position shown in Figure 6.

30 The slide members —9— are then adjusted along their respective arms —5— until their concave seats —10— rest upon the underlying bars —1— and are then tightened in place by the set screws —11—.

35 The lower grate sections —14— are then placed one by one through the fuel door onto the supporting frame —2— with their flanges —15— engaged in their corresponding recesses —12— and against the adjacent lugs —13— and at the same time causing the lugs —16— to be saddled upon the outer ends of the arms —5— as shown more clearly in Figures 6 and 7, thereby locking the grate sections to the underlying supporting frame —2— against lateral or radial displacement.

40 The hub section —22— is then inserted through the fuel door opening and placed in operative position to extend through the frame hub —3— with its upper end journaled upon the ballbearings —25— in a manner shown more clearly in Figure 2.

45 The grate section —28— is then inserted through the fuel opening and placed upon the square upper end of the hub —22— thereby establishing a locking connection between said hub and grate section to cause the latter 50 to rotate as the hub —22— is turned about its axis.

55 The grate section —33— is also inserted through the fuel opening and placed in operative position with its hub resting upon the hub of the section —28— and its wings —32— extended radially between the wings —29— of the sections —28—, and its flanges —35— seated in the recesses —34— of the section —28— thereby locking the two sections —28— and —33— together against relative

rotation while permitting both to be rotated by the angular movement of the hub —22— about its axis.

60 The ash supporting ring —37— is then inserted through the fuel opening and placed upon the hub of the grate section —33— around the perforated central portion of the hub as shown in Figure 2.

65 It is now clear that the supporting frame —2—, grate segments —14—, hub —22— and grate sections —28— and —33—, together with the ash supporting ring —37— are all placed in operative position in such manner as to be self-retaining by their own weight without the use of extra tools other than the 70 means for tightening the set screws —11— and —47—.

75 When these parts have been assembled in the manner described the link —50— is attached to one or the other of the pivotal pins —49— and to the lever —52— which in turn is seated at its lower end in one or the other of the sockets —68— depending upon the degree of angular movement required for 80 shaking or dumping the grates.

85 For example, if only a slight angular movement is required the lever —52— will be placed in the innermost socket —68— and if a greater angular movement is required for 90 the dumping it will be placed in the second socket but if complete dumping is required it will be placed in the third or outermost socket.

95 In either of these adjustments the backward and forward movement of the lever —52— will be transmitted through the link —50— to the crank arm —46— and thence to the hub —22— which in turn will effect the corresponding angular movement of the 100 grate section —28— and, through the interlocking connections shown in Figure 3, will cause the same angular movement of the grate section —33—.

105 It is, of course, obvious that when removing the various elements of the grate the order of assembly described will be reversed.

110 If it should be necessary or desirable to extend the link —50— forwardly at a different angle from that shown the lever supporting member —69— may be removed by loosening the bolt —70— and replaced to register another one of its slots —75— with the flange —74— thereby adjusting the member —69— angularly to conform to the changed angle of the lever —50— which, of course, necessitates the changing of hand lever —52— to move forwardly and rearwardly in a substantially vertical plane.

115 When the hand lever —52— is seated in the outermost socket —68— it may be moved through a longer arc than when in either of the other sockets thus permitting the spaces between the segments —28— and —33— to be registered with the openings —17— in the lower grate, and allowing the ashes to be 120

dumped through said openings, this dumping operation being expedited by limited oscillations of the grate sections —28— and —33—.

On the other hand when the lever —52— is seated in either one of the inner sockets —68— its arc of movement will be more limited, thereby retaining the grate sections —28— and —33— in position to cover the openings —17— while permitting the limited oscillation of said sections.

The construction shown and described is particularly simple and efficient but obviously various changes can be made in the detail construction without departing from the spirit of the invention.

What I claim is:

1. In a heater grate, a grate-supporting frame having a central tubular hub and arms radiating outwardly therefrom, and a plurality of grate segments mounted edge to edge circumferentially around the hub, said frame and segments having interlocking connections for holding the segments against radial displacement.

2. In a heater grate, a grate-supporting frame having a central tubular hub and arms radiating outwardly therefrom, and a plurality of grate segments mounted edge to edge circumferentially around the hub, said frame and segments having interlocking connections for holding the segments against radial displacement, and interlocking connections between the segments and arms for holding said segments against circumferential movement relatively to the frame.

3. In a heater grate, a grate-supporting frame having a central tubular hub and arms radiating outwardly therefrom, said arms having lengthwise slots, supporting members movable in said slots and adapted to rest upon the base of the heater, and a grate mounted upon the frame.

4. In a heater grate, a grate-supporting frame having a central tubular hub and arms extending outwardly therefrom in circumferentially spaced relation, frame-supporting members slidable along and upon said arms, and a plurality of grate segments arranged edge to edge circumferentially upon the frame around the hub, said frame and segments being provided with interlocking connections for holding the segments against circumferential movement relatively to the frame.

5. In a heater grate, a grate-supporting frame having a central tubular hub and arms extending outwardly therefrom in circumferentially spaced relation, frame-supporting members slidable along and upon said arms, and a plurality of grate segments arranged edge to edge circumferentially upon the frame around the hub, said frame and segments being provided with interlocking connections for holding the segments against radial movement relatively to the frame.

6. A grate-supporting frame comprising a tubular hub having a series of peripheral recesses arranged in uniformly spaced relation circumferentially about its axis and a corresponding number of grate segments mounted on the frame and provided with pendent lugs engaged in said recesses.

7. A supporting-frame for heater grates comprising a tubular hub having a plurality of radially projecting arms arranged in uniformly spaced relation circumferentially, webs connecting said arms and having their central portions provided with bearing surfaces disposed in a plane above that of the arms and a plurality of grate segments mounted on the frame and arranged edge to edge circumferentially, said segments having their outer ends resting upon the raised bearing surfaces of the webs.

8. A supporting-frame for heater grates comprising a tubular hub having a plurality of radially projecting arms arranged in uniformly spaced relation circumferentially, webs connecting said arms and having their central portions provided with bearing surfaces disposed in a plane above that of the arms and a plurality of grate segments mounted on the frame and arranged edge to edge circumferentially, said segments having their outer ends resting upon the raised bearing surfaces of the webs, and interlocking connections between said segments and the hub of the frame to hold the segments against radial displacement.

9. A supporting-frame for heater grates comprising a tubular hub having a plurality of radially projecting arms arranged in uniformly spaced relation circumferentially, webs connecting said arms and having their central portions provided with bearing surfaces disposed in a plane above that of the arms and a plurality of grate segments mounted on the frame and arranged edge to edge circumferentially, said segments having pendent lugs saddled upon the arms of the frame to hold the segments against circumferential movement relatively to the frame.

10. In a heater grate, a frame having a central opening and outbearing surfaces arranged in uniformly spaced relation circumferentially around the opening, grate segments mounted edge to edge circumferentially around and upon the frame and normally resting upon said bearing surfaces, interlocking connections between said segments and frame to hold the segments against circumferential movement relatively to the frame, a hub rotatably mounted upon the central portion of the frame and extending through the opening therein, a grate section mounted upon the upper end of the hub to rotate therewith and provided with diametrically opposite wings, an additional grate section mounted upon the central portion of the first named grate section and provided with diametrical-

ly opposite wings disposed in the same plane as and between the first named wings, said sections having interlocking connections one with the other to cause them to rotate in unison with the hub, and means for rotating the hub.

11. In a heater grate, a grate-supporting frame having a central opening, a hub journaled on the frame and extending through the opening therein some distance below the frame, a grate section mounted on the hub to rotate therewith, a lever support operably mounted upon the base of the heater to extend outwardly therefrom and provided with a series of bearings at different distances from the axis of the hub, a hand lever adapted to be operably fulcrumed on either of said bearings for movement in opposite directions upon its fulcrum, and means actuated by the movement of said lever for effecting an angular movement of said hub and grate section carried thereby.

12. In a heater grate, a grate-supporting frame having a central opening, a hub journaled on the frame and extending through the opening therein some distance below the frame, a grate section mounted on the hub to rotate therewith, a lever support operably mounted upon the base of the heater to extend outwardly therefrom and provided with a series of bearings at different distances from the axis of the hub, a hand lever adapted to be operably fulcrumed on either of said bearings for movement in opposite directions upon its fulcrum and means actuated by the movement of said lever for effecting an angular movement of said hub and grate section carried thereby, said fulcrumed member being adjustable to different positions about a vertical axis, and means for holding the member in its adjusted position.

13. In a heater grate, a non-rotatable main grate and supporting means therefor, in combination with separate rotatable grate sections co-axial with said main grate and each provided with diametrically opposite wings overlying the main grate, the wings of both sections being disposed in the same horizontal plane, and means for locking said grate sections to each other to cause them to rotate in unison.

14. The combination with a non-rotatable main grate having relatively large openings therethrough for the discharge of ashes, supporting means for the main grate, additional grate sections rotatable about the axis of the main grate and provided with diametrically opposite wings movable into and out of registration with said openings, the wings of both sections being disposed in the same horizontal plane, and means for locking said sections to each other to cause them to rotate in unison.

15. In a heater, a grate-supporting frame

having a central opening and raised out-bearing surfaces equal distances from the opening, a hub journaled on the frame and extending through said opening to rotate therein, a main grate resting upon said raised bearing surfaces of the frame, interlocking connections between the main grate and frame to hold those parts against relative angular movement, said main grate being provided with relatively large openings through which the ashes may be dumped, a grate section mounted upon the hub to rotate therewith and provided with diametrically opposite wings movable into and out of registration with said openings, and means for effecting an angular movement of the hub.

16. In a heater, frame-supporting means mounted upon and within the base of the heater, a grate supporting frame loosely mounted upon said supporting means for upward displacement therefrom, co-operative means between the frame and those supporting means for holding the frame against circumferential or lateral displacement from the supporting means, said frame being provided with a central opening, a hub loosely journaled on the frame for upward displacement and extended through said opening, a plurality of grate segments loosely mounted upon the frame for upward displacement, interlocking connections between each segment and the frame to hold those parts against relative angular movement, said main frame being provided with relatively large openings at diametrically opposite sides of the centers to permit the dumping of ashes therethrough, a grate section mounted upon the upper end of the hub to rotate therewith and provided with diametrically opposite wings, an additional grate section mounted upon the first named grate section to rotate therewith and provided with diametrically opposite wings midway between the wings of the first named section, said wings being disposed in the same plane and movable into and out of registration with the openings in the main grate, the portion of the second named grate section connecting its wings being extended across the upper end of the hub and central portion of the first named grate section and provided with air openings therethrough, an ash supporting ring mounted upon the upper surfaces of both of the grate sections around the apertured central portion of the second named grate section and provided with air passages in its underside communicating with the openings in the grate sections and with the central opening in the ring.

In witness whereof I have hereunto set my hand this 8th day of November, 1929.

FRANK A. AUSTIN.
